Specification of Letters Patent. Patented July 28, 1914.

Application filed July 11, 1913. Serial No. 778,471.

To all whom it may concern:

Be it known that I, ROBERT MIEHLE, a citizen of the United States, and a resident of Plymouth, in the county of Marshall and State of Indiana, have invented certain new and useful Improvements in Printing-Presses; and I do hereby declare that the following is a full, clear, and exact description thereof, reference being had to the accompanying drawings, and to the letters of reference marked thereon, which form a part of this specification.

This invention relates to improvements in inking mechanism for printing presses of that class having a cylindric impression member, a reciprocating bed and an ink table which reciprocates with the bed, and in which the ink is distributed upon the said ink table by means of distributing rollers extending transversely over the same.

The principal object of my invention is to provide an improved construction in the means used in such a printing press for actuating and supporting the ink-distributing rollers and for supplying ink thereto.

A further object of my invention is to provide an improved means for imparting to the distributing rollers an initial rotation with a velocity or surface speed substantially equal to the speed of the ink table, immediately prior to the contact of such rollers with the ink table. This feature of my invention is in the nature of an improvement upon the devices constituting the subject-matter of my prior U. S. Letters Patent, No. 558,594.

Still another object of my invention is to provide an improved construction in adjustable journal bearings for ink-distributing rollers.

In the accompanying drawings—Figure 1 is a view in side elevation of a portion of the printing press with parts of the frame removed, showing the position of the several parts during the movement of the bed and ink table in a direction toward the distributing rollers; Fig. 2 is a view in cross-section taken on line 2—2 of Fig. 1; Fig. 3 is a view in side elevation, similar to Fig. 1, showing the position of the parts at the time the ink table is engaging the distributing rollers and moving in the same direc-

tion; Fig. 4 is a view in side elevation, showing the position of the parts at the commencement of the forward stroke of the ink table, when the latter is moving in a direction toward the impression cylinder, as indicated by the arrow; Fig. 5 is a fragmentary top view of the printing press, showing the features constituting my invention; Fig. 6 is a detail view, in end elevation, of one of the roller journal bearings; Fig. 7 is a detail view in side elevation of the roller journal bearing shown in Fig. 6.

Referring to the drawings:—The frame of the printing press consists of two parallel side frame members 10 which are rigidly joined by transverse frame members. On the frame of the press is mounted the impression cylinder 11, said cylinder being like those ordinarily used in presses of this type. Immediately below the said impression cylinder is located the reciprocating bed 12, the same being supported by the frame, as hereinafter described, and adapted to carry the printing-form from which the impression is transferred, at each stroke of the bed, to the paper stock carried by the revolving impression member. One end portion of the bed constitutes the ink table 13, the same being provided with a smooth surface to which a quantity of ink is transferred, by an oscillating ductor roller 15, and on which the same is distributed by means of distributing rollers 14^a and 14^b. Said ductor roller 15 transmits the ink to the ink table from an ink fountain 16, located on the frame at the end of the press beyond the path of the ink table.

The reciprocating bed 12 and ink table 13 will be actuated by means such as are ordinarily employed in presses of this type. Such means are not shown in the accompanying drawings; an illustration of the same being unnecessary for an understanding of the present invention. A plurality of form inking rollers 18, 18 are mounted upon the side frame members 10 and extend transversely of the press immediately above the reciprocating bed and adjacent to the impression cylinder 11, said form inking rollers being adapted to supply ink to the printing form carried by the reciprocating bed,

said ink being transferred to said form inking rollers by the passage of the ink table beneath and in contact therewith.

Now referring to the features of the press more directly relating to and embodying my present invention, these parts are shown in the drawings as follows: Integral with and extending longitudinally of the frame and between and adjacent to the side frame members thereof, are two I-beam members 19, 19, the upper flanges of which are provided with upwardly facing bearing surfaces 19^a, 19^a. Upon the said bearing surfaces 19^a, 19^a, rest two longitudinally arranged slider frames 20, each comprising transverse journals 20^b secured at their ends in parallel, vertical frame plates 20^c, 20^c, a plurality of bearing rollers 20^d being mounted upon said journals 20^b between said side plates. The lower margins of the said side plates extend downward below the plane of the bearing surfaces of the rollers (Fig. 2), and engage parallel retaining grooves 19^b formed at opposite sides of the bearing surfaces 19^a, 19^a of the I-beam members 19. Upon the rollers 20^d of these slider frames 20 rests the bed 12; said bed being provided upon its under surface with longitudinal, rectangularly formed ribs or projections 12^a having downwardly facing bearing surfaces 12^b engaging the said bearing rollers. The said projections 12^a, 12^b are embraced by the plates 20^c, thus preventing any transverse movement of the bed relative to the slider frames.

A positive reciprocating movement is imparted to said slider frames by the following means:—The lower flange of one of the I-beam members 19 is provided, along its central portion, with an inwardly projecting extension 22 having upwardly facing rack teeth 23 formed integral therewith. Upon the under surface of the bed 12 and in the plane of the rack teeth 23, is formed a rack bar 24, the same extending longitudinally of said bed and integral therewith. Interposed between said rack teeth 23 and the rack bar 24, is a gear wheel 25. The said gear wheel 25 is rotatively mounted upon a stub shaft 26, the same being secured to a depending web 27 integral with the inner vertical plate 20^c of the adjacent slider frame 20. By this construction, driving force is applied to the reciprocating slider frame, maintaining the same always in the same relation to the bed; the intermeshing of the gear wheel 25 with the movable rack bar 24 of the reciprocating bed 12 and with the stationary rack teeth 23 acting to impart a positive movement to the slider frame. The direction of movement of the slider frames will at all times correspond to the direction of movement of the bed, but the rate of travel of said slider frames will be one-half that of the bed.

At the end of the press adjacent to the ink fountain 16, are mounted the hereinbefore mentioned ink-distributing rollers 14^a and 14^b. The said rollers are composed of the soft material ordinarily used in the printing art in the manufacture of inking rollers, and said rollers extend transversely of the frame, in such position as to engage the surface of the ink table as the same passes beneath them. The roller journals 30^a and 30^b of the rollers 14^a and 14^b, respectively, are mounted in bearings 31, 31, secured to the side frame members. The bearings 31 at the adjacent ends of the journals are preferably of the open type, to be hereinafter more fully described, and the bearings at the opposite ends of the journals are preferably of the ordinary plain or closed type. The roller journals 30^a and 30^b are of a length slightly greater than the distance between the bearings, thus permitting a limited degree of endwise movement of the rollers. The said open type of bearings provided at the adjacent ends of the distributing rollers permits a free vertical movement of one end of each roller in an upward direction relative to the ink table. In order that an initial rotation may be imparted to the rollers, prior to their contact with the ink table, devices are provided as follows:

A horizontal arm 33 is rigidly secured to the slider frame 20 which is located at the side of the press adjacent to the ends of the rollers provided with the open type of bearings 31. Said arm extends forward from the slider frame and is located substantially in the same horizontal plane with the reciprocating bed. The arm 33 is supported in rigid connection with the outer vertical plate of the slider frame by means of a vertical member 34, and is also supported in sliding engagement with a guide 33^a integral with the adjacent side frame member 10.

The extreme forward portion of the said arm is provided with an elongated block or shoe 35 having an upwardly facing surface which is horizontal at its central part and slightly inclined downwardly at its ends. A layer of leather or similar friction increasing material 35^a is applied to the surface of the shoe. The frictional surface of said shoe lies in a horizontal plane a short distance above that of the surface of the ink table, and is adapted to engage friction rollers or collars 36^a, 36^b mounted upon the journals 30^a, 30^b of the distributing rollers 14^a, 14^b adjacent to the journal bearings 31, 31. The diameter of said friction collars is considerably less than that of the distributing rollers and preferably one-half of the diameter of said distributing rollers.

Adjacent to the distributing roller 14^b is mounted a small transfer roller 37 substan-

tially one-half the diameter of the said roller 14^a. Said roller 37 extends parallel with the said roller 14^b and is in contact therewith throughout its length. Plain bearings 37^a support the journal of the transfer roller 37. Said bearings are mounted upon the side frame members and are of a sufficient height to prevent the contact of the transfer roller 37 with the ink table 13, as the same passes beneath the said roller.

Referring now to the means whereby the ink may be supplied or fed intermittently and at regular intervals in the required quantity to the ink table, these devices are made as follows: The ink fountain 16 consists of a tank or reservoir 38 extending across the extreme end of the press beyond the outer end of the ink table when the same is at the outer limit of its stroke; said tank being mounted upon a bracket 39, integral with the side frame member. Within the tank or reservoir 38 is a horizontal roller 40 journaled at its ends in the end walls of the tank and adapted to be partially immersed in the ink which is contained in said tank. A rotative movement is imparted to the said roller 40 by means of suitable actuating mechanism designed to provide for giving a variable extent of rotative movement to the roller, as heretofore common in such ink fountains.

The ink is carried from the roller 40 within the tank to the transfer roller 37, by means of the ductor roller 15, the same having its journals rotatably mounted at the ends of arms 41, which are rigidly secured to a rock shaft 42 journaled at its extremities in the side frame members. The said arms 41 are of sufficient length to permit the ductor roller to be swung through an arc extending from the surface of the roller 40 to the surface of the transfer roller 37 (Figs. 1 and 3), and also to be swung into a position to be engaged by the surface of the ink table.

The swinging movement of the ductor roller is effected by means as follows: Rigidly secured to the shaft 42, adjacent to one of the side frame members, is a lever arm 43 arranged at an angle of approximately 45° to the arms 41. Below the reciprocating bed is a cam shaft 44 extending transversely of the press and located below the reciprocating bed. The said cam shaft is driven from a driving shaft (not shown) by gearing so arranged that the relative speeds of rotation of the main driving shaft and the said cam shaft will be such that the latter will be rotated once during the travel of the reciprocating bed in one direction. Upon the cam shaft 44 is rigidly mounted a cam member 45, the periphery of which is of an irregular shape and adapted to be constantly engaged by a cam roller 46. The said cam roller 46 is rotatably mounted upon and between the extremities of a lever arm 47;

said lever being pivotally mounted at its lower extremity on the frame of the press. The upper extremity of the lever arm 47 is pivotally connected with a link 48 which is similarly connected with the extremity of the lever arm 43. The periphery of the said cam member 45 is so shaped as to transmit an intermittent swinging movement to the ductor roller 15, the said cam having a semi-circular portion 45^a of a uniform minimum radius, a portion 45^b of a maximum radius, extending through a somewhat lesser arc than that of the said portion 45^a, and two inwardly and outwardly deflected portions 45^c and 45^d extending between the said portions 45^a and 45^b. The said deflected portions of the periphery of the cam member effect an intermittent motion of the ductor roller, through the medium of the coacting cam roller 46 and the several links and levers described, during a single revolution of the said cam member, in the following manner: The portion 45^a effects the contact of ductor roller with roller 40 of the ink fountain during substantially one-half of the revolution of the cam member. The portion 44^c, by reason of its increasing radius, effects the swinging movement of the ductor roller 15 from the ink fountain 16 to the transfer roller 37, the same remaining in contact with said transfer roller during the travel of the cam roller 46 over the cam surface 45^a. The cam surface 45^b being similar in contour to the opposite cam surface 45^c, by the action of the same, the ductor roller is swung back to its original position, or into contact with the ink fountain roller. It is apparent that the contour of the periphery of the cam member 45, as well as its position upon the driving shaft 44, is predetermined, in such manner that the movements given thereby to the ductor roller will conform to the movements of the reciprocating bed and the ink table.

Having described the construction of the several parts embodying my invention, the manner in which these several parts operate, relative to each other, will now be stated.

In Fig. 1 of the drawings, the reciprocating bed is shown, as indicated by the arrow, as moving in a direction toward the distributing rollers 14^a and 14^b, the ink table 13 having passed from beneath the form inking rollers 18, 18, to which a quantity of ink has been transferred from said ink table. At this time the slider frames 20 are simultaneously moving in the same direction as, but at one-half the rate of speed of, the bed, as is also the shoe 35, the frictional bearing surface of which is shown as engaging the friction collar 36^a of the distributing roller 14^a and about to engage the collar 36^b of the roller 14^b immediately beyond the same. The coaction of the shoe with the roller 14^a produces a rotation of the roller, 130

and at the same time slightly lifts the adjacent end of the roller, the journal of which rises within its bearing 31. The same action takes place in connection with the roller 14^b, which is similarly engaged by the frictional bearing surface of the shoe 35 as the movement of the same continues. The rate of rotative movement imparted to the distributing rollers 14^a, 14^b obviously depends upon the rate of movement of the shoe and upon the diameter of the collars 36^a, 36^b. The rate of movement or linear velocity of the shoe having been determined to be one-half of that of the bed and ink table, and the diameter of the collars 36^a, 36^b to be one-half of the diameter of the distributing rollers, 14^a, 14^b, the resulting rate of surface speed of the rollers will be substantially equal to that of the ink table.

20 The slight raising of the rollers within the open bearings 31, permits the forward margin of the ink table 13 to pass freely beneath the distributing rollers without contact therewith. Immediately upon the passage of the forward margin of the ink table beneath the said rollers, the same are gradually lowered into contact with the surface of the ink table by the passage of the horizontal portion of the frictional surface of the shoe 30 from beneath the collars 36^a and 36^b and the contact of the rollers with the downwardly inclined end portion of the surface of the shoe. When the ink table reaches the position shown in Fig. 3, the same has passed beneath both of the distributing rollers, the roller 14^a is resting entirely upon the ink table and the roller 14^b is about to be released by the shoe 35. In this position of the parts, the ductor roller has been swung upward in position to engage the transfer roller 37, and to come in contact with the ink table. The ink is thus transmitted directly to the ink table by the contact of the ductor roller with the ink table, as well as indirectly through the medium of the distributing rollers 14^a, 14^b and the intermediate transfer roller 37. The ink will be distributed upon or over the surface of the ink table by the action of the distributing rollers 50 as the table passes thereunder. In Fig. 4, the bed and ink table are shown as having reached the outer end of their path of movement, and at the commencement of their return movement. The reversal of direction 55 of movement of the bed and ink table is accompanied by a swinging movement of the ductor roller 15 to its original position in contact with the ink fountain roller 40, the said ductor roller being actuated by the cam 60 member and intermediate links and levers, so that the same is lifted from the ink table at substantially the same time that the movement of the ink table in the opposite direction begins. By this arrangement, the ductor roller does not remain in contact with

the ink table during any portion of its return travel or movement toward the form-inking rollers.

The advantage gained by the employment of the actuating devices described for the ductor roller, may best be understood from the following: In printing presses of this type it is the usual practice to control the quantity of ink applied to the ink table by varying the area of the ductor roller surface which coacts with the inked surface of the ink fountain roller, by providing driving means for the said ink fountain roller, acting to transmit a greater or less degree of rotation to said ink fountain roller during the time that the ductor roller is in contact therewith. The ductor roller, therefore, will receive from the ink fountain roller during each period of its contact therewith, a quantity of ink in the form of a strip extending longitudinally of the ductor roller, said strip being of greater or less width depending on the extent of rotation imparted to the ink fountain roller during the time the ductor roller remains in contact with said fountain roller. When, therefore, the ductor roller is swung upward into contact with the transfer roller and with the ink table, a portion of the ink will be transferred to the surface of the said transfer roller in the form of a strip of corresponding width. By reason of the relatively small diameter of the said transfer roller, the strip of ink will cover a greater or less portion of the surface of the transfer roller, according to the width of the strip transferred. The contact of the said transfer roller with the adjacent distributing roller results in a further transfer of the strip of ink, and, by reason of the large diameter of the said distributing roller relatively to that of the transfer roller, a further distribution of the ink will take place, in the coaction of the transfer roller with the surface of the distributing roller. The distributing roller in turn transfers and distributes the ink upon the ink table by its engagement therewith. A portion of the strip of ink upon the surface of the ductor roller will be transferred directly to the ink table by the rotative or rolling contact of the ductor roller therewith, and at each revolution of the ductor roller a strip of ink will be applied to the ink table, extending entirely across the same. It will, therefore, be apparent that the distribution of ink upon the ink table by its direct contact with the ductor roller is accomplished by the application to the ink table of a plurality of parallel strips of ink. In the return movement of the ink table, the effect of subsequently retaining the ductor roller in contact with the table, will be a tendency in the ductor roller to pick up or remove a portion of the ink already applied to the ink table. This

tendency will be greater in cases in which a narrow strip of ink has been transferred from the ductor roller to the ink table, for the reason that a larger surface of the ductor roller will in that case remain comparatively free of ink, and hence will pick up the ink more readily. Taking into consideration the fact that the primary function of the ductor roller is to apply the ink to, and not to distribute the ink upon, the ink table, the advantage gained by removing the ductor roller from contact with the ink table at the instant of reversal of direction of the ink table, will be obvious. A further advantage gained in removing the ductor roller from contact with the ink table at the beginning of its movement away from the ink fountain is, that the ink table being substantially stationary at the instant of removal 20 the ductor roller is rendered non-rotative during the movement from the ink table to and in contact with the ink fountain roller, thus eliminating the liability of injury to the ductor roller, which being composed of 25 the usual soft material would be injured or torn by the repeated jar or shock resulting from the contact of a rotative ductor roller with the ink fountain roller. It is to be understood, however, that the above description 30 of the manner in which the ink is transferred from the ink fountain, applies only under certain conditions of operation, for it is apparent that the entire surface of the ductor roller may receive a coating of ink, 35 and in such case the application of the ink to the ink table in the form of strips would not occur. The advantages gained by removing the ductor roller at the time of reversal of movement of the ink table, apply 40 under all conditions of ink distribution.

Referring further to the operation of the various parts, and in connection with Fig. 4, the return movement of the bed and table is also accomplished by movement of the slider frames in the same direction, and a like movement of the shoe 30. As before, the distributing rollers are lifted from the table by the passage of the said shoe beneath the collars 32^a and 32^b just prior to the passage of the ink table from beneath the distributing rollers. The bed continues its movement toward the impression cylinder 11, and beneath the form-inking rollers where the form is properly inked prior to the transfer of the impression 50 upon the stock carried by the impression cylinder. This movement continues until the ink table has passed beneath the form-inking rollers and transferred a quantity of ink thereto. Simultaneously with the movement 55 of the bed and ink table, the shoe 30 continues its movement and moves past and out of engagement with the distributing rollers 14^a and 14^b, the same being again lowered to their original positions. With the subsequent reversal of direction of movement 60

of the reciprocating bed, the operation just described is repeated.

It is to be understood that any number of distributing rollers may be used, all of which may be mounted in the manner described 70 herein illustrated and described.

By mounting the roller-actuating device upon the slider frame rather than upon the bed, as I have shown in my prior U. S. Letters Patent, No. 555,594, advantages are obtained which will be understood from the following: The weight of the reciprocating bed is materially reduced, thus lessening the 75 force required to overcome the momentum of the bed at the end of each stroke of the same. A further advantage lies in the fact that the shoe is moving at a materially lessened speed when it comes into engagement with the distributing rollers, so that the 80 shock or jar due to the initial contact of the shoe with the distributing rollers is greatly decreased, and the wear upon the journals and bearings correspondingly lessened.

The bearings 31 (Figs. 6 and 7), in which 90 the ends of the roller journals are mounted, are shown in the drawings as provided with improved features of construction by which the same are adapted to be adjusted laterally as well as vertically. Said bearings 95 comprise a rectangular bearing block 50, the inner lateral face of which is provided with a longitudinal groove or channel 50^a. The said channel engages a tongue or projection 50^b, formed integral with a longitudinal and 100 outwardly extending flange 51 on the side frame member 10. The said bearing block is further provided, adjacent to one of its ends, with a longitudinal slot 50^c through which 105 extends a bolt 52, the same being anchored in the flange 51 of the side frame member. A vertical bore 50^d extends through the bearing block adjacent to the opposite end of the same, and within said bore is loosely mounted a stem 53, the upper end of which is 110 shaped to form a U-shaped yoke 54. The roller journal 55 is retained within the U-shaped yoke and adapted to have a vertical movement therein. Formed integral with the yoke 54 is a lug 56, which extends over 115 the bearing block 50 and is provided with a vertical bore 56^a. A stud 57 fits loosely in said bore and is provided at its lower extremity with screw threads which engage a threaded bore 58 in the bearing block. 120 The stud 57 is further provided with an integral collar 57^a located immediately above its threaded extremity; said collar bearing upwardly against the lower face of the lug 56. The upper extremity of the stud is likewise screw threaded and carries a nut 59, which is applied after the stud is inserted 125 upwardly through the bore 56. Said nut 59 is secured to the stud by means of a pin 59^a extending through the nut and a transverse 130

aperture of the stud. A spring washer 60 is interposed between the nut and the adjacent face of the lug, this insuring the constant bearing of the collar 57 against the lug. The purpose of this form of bearing is to permit adjustment of each roller, not only vertically to compensate for variation in size in, or shrinkage of, the roller, but also to provide for lateral adjustment of said bearing, whereby the axis of the roller may be slightly inclined from a line at right angles to the side frame member of the press. This lateral adjustment is accomplished by a loosening of the bolt 52 and a shifting of the block 50. This operation will necessitate a slight rotative movement of the yoke 54 relative to the block, particularly in cases where the bearing at the opposite end of the roller journal is not shifted to a like extent. The loose mounting of the stem 57 within the block 50, permits this necessary movement, as does also the diameter of the bore 57^a of the lug, which allows free rotative movement of the stud 58 therein. The bearing of the collar and spring washer against the lug holds the yoke 54 in position, after the same is adjusted. The vertical adjustment of the bearing is accomplished by merely raising or lowering the stud relative to the bearing block. This improved form of bearing permits an accurate and convenient adjustment of the rollers.

It is to be understood that the devices herein illustrated and described may be variously modified without departing from the spirit of my invention, and I do not, therefore, desire to be limited to the construction set forth, except so far as pointed out in the appended claims.

40 I claim as my invention:

1. In a printing press, the combination of a reciprocating ink table, a distributing roller, a movable member having reciprocatory movement upon the frame and moving thereon at a less speed than that of the reciprocating ink table, said member being provided with a frictional bearing surface adapted to act on said distributing roller to impart rotative movement thereto.

50 2. In a printing press, the combination of a reciprocating bed, an ink table moving with said bed, a distributing roller provided with a friction surface, a slider frame, and a plurality of rollers mounted on said slider frame and supporting said reciprocating bed; said slider frame being provided with a frictional bearing surface adapted to engage said friction surface of said roller.

60 3. In a printing press, the combination with the press frame, of a reciprocating ink table, a distributing roller, a slider frame mounted on the press frame and supporting the reciprocating ink table, said slider frame having reciprocatory movement at a less speed than that of the ink table and being

provided with a frictional bearing surface adapted to act on said distributing roller to impart rotative movement thereto.

4. In a printing press, the combination of a reciprocating bed, an ink table moving with said bed, a distributing roller provided with an annular friction surface materially smaller in diameter than said distributing roller, a slider frame, anti-friction rollers mounted on the slider frame and supporting said reciprocating bed; said slider frame being provided with a frictional bearing surface of said roller, and driving means acting to impart positive reciprocatory movement to said slider frame at one-half of the speed of the reciprocating bed.

5. In a printing press, the combination of a reciprocating bed, an ink table moving with said bed, a distributing roller provided with an annular friction surface of a diameter materially less than that of said distributing roller, a slider frame, a plurality of anti-friction rollers supporting said reciprocating bed and in rolling engagement with a bearing surface of the press frame, and means for imparting a reciprocatory movement to said slider frame corresponding in a direction to, and at a speed materially less than, that of the said bed; said slider frame being provided with an arm carrying a shoe provided with an upwardly facing, frictional bearing surface adapted to engage said friction surface of said roller and to impart an initial rotative movement to said distributing roller.

6. In a printing press, the combination of a reciprocating ink table, a distributing roller, adapted to be engaged by said ink table, and a reciprocating slider frame having movement at a speed less than that of said ink table and provided with means for slightly raising said roller and imparting rotative movement thereto immediately before said ink table passes beneath said roller.

7. In a printing press, the combination with the press frame of a roller bearing comprises a bearing member capable of horizontal adjustment upon said press frame and provided with a vertical stem removably retained within a vertical bore of the bearing member, and provided with a lug integral with said stem, and having a vertical aperture, a stud loosely retained within said aperture by said lug and in screw-threaded engagement with the said bearing member, and means for preventing vertical movement of said stud relative to the lug.

8. In a printing press, the combination with the press frame, of a roller bearing comprising a block removably secured to the press frame and provided with a vertical bore, a bearing member provided with a stem removably retained in said vertical bore, and with a lug, integral with said stem,

provided with a vertical aperture, a stud loosely retained in the aperture of said lug and in screw-threaded engagement with said block, and means for preventing vertical movement of said stud relative to the lug.

9. In a printing press, the combination with the press frame, of a roller bearing comprising a bearing member mounted upon the press frame and capable of horizontal adjustment, said bearing member being provided with a vertical stem removably retained in a vertical bore of said bearing member frame, and a lug integral with said bearing member and provided with a vertical aperture, a stud rotatably retained in the aperture of said lug and in screw-threaded engagement with the bearing member, said stud being provided with a collar integral therewith, in contact with the lower face of said lug, and a spring washer integral between the head of the stud and the upper face of said lug.

10. In a printing press, the combination with the press frame, of a roller bearing comprising a shiftable bearing block mounted upon the frame, a bearing member provided with a vertical stem, said bearing block being provided with a vertical bore to receive said stem, and means for vertically adjusting said bearing member comprising a stud having screw-threaded engagement with said bearing block, and engaging a vertical bore of said bearing member, said bore being of substantially greater diameter than said stud to permit a limited rotative movement of said bearing member relative to said bearing block, and means for preventing endwise movement of said stud relative to said bearing member.

11. In a printing press, the combination with the press frame, of a roller bearing comprising a block removably secured to the press frame and provided with a vertical bore, a bearing member provided with a stem removably retained in said vertical bore, and with a lug, integral with said stem, provided with a vertical aperture, a stud rotatably retained in the aperture of said lug and in screw-threaded engagement with said block, said stud being provided with a collar integral therewith, in contact with the lower face of said lug, and a spring washer interposed between the head of the stud and the upper face of said lug.

12. In a printing press, the combination of a reciprocating ink table, an ink fountain, a ductor roller mounted to be oscillated from

said ink fountain into position to be engaged by the surface of said ink table, and means giving intermittent oscillatory movement to said ductor roller, acting to maintain the said ductor roller in engagement with the ink table during the movement of said table outwardly or toward the ink fountain and to effect the disengagement of said ductor roller from said table at the beginning of the movement of said table inwardly or away from the ink fountain.

13. In a printing press, the combination of a reciprocating ink table, an ink fountain, a distributing roller, a transfer roller mounted to constantly engage the distributing roller, an oscillatory ductor roller, and means for imparting intermittent oscillatory movement to said ductor roller, acting to hold said roller in position for contact with said transfer roller and for engagement with the surface of said ink table, during a portion of the movement of the ink table in one direction, and to remove said ductor roller from contact with said transfer roller and the surface of the ink table at the beginning of the movement of the ink table in the opposite direction.

14. In a printing press, the combination of a reciprocating ink table, a distributing roller, an ink fountain mounted at one end of the frame of the press, beyond the path of movement of the ink table, a ductor roller, supporting arms for said ductor roller pivotally mounted upon the frame of the press, a cam shaft, a cam member mounted upon said cam shaft, and means in operative engagement with said cam member and with said arms of the ductor roller, imparting intermittent oscillatory movement to said ductor roller and acting to carry the said ductor roller into position to engage said ink table and to supply ink to said distributing roller, during a portion of the movement of the ink table in one direction, and to remove the ductor roller from engagement with the said ink table at the beginning of the movement of the ink table in the opposite direction.

In testimony that I claim the foregoing as my invention I affix my signature in the presence of two witnesses, this first day of July, A. D. 1913.

ROBERT MIEHLE.
